ABSTRACT

A new *Dianthus* plant designated 'KLEDP19289' particularly distinguished by salmon-pink double flowers, composed in round, small sprays and an upright habit, is disclosed.

1 Drawing Sheet

1

Genus and species: *Dianthus caryophyllus*.
Variety denominations: 'KLEDP19289'.

BACKGROUND OF THE NEW PLANT

The present invention comprises a new and distinct variety of *Dianthus*, botanically known as *Dianthus caryophyllus*, and hereinafter referred to by the variety name 'KLEDP19289'. 'KLEDP19289' originated from a cross from between the female *Dianthus* parent 'DCP-2009-0047' (unpatented) and the male *Dianthus* parent 'DCP-2007-0035' (unpatented) in The Netherlands in summer 2014.

In September 2015, 'KLEDP19289' was first vegetatively propagated by vegetative stem cuttings. 'KLEDP19289' was found to reproduce true to type in successive generations of asexual propagation in Stuttgart, Germany via vegetative stem cuttings.

SUMMARY

The following are the most outstanding and distinguishing characteristics of 'KLEDP19289' when grown under normal horticultural practices in Latina, Italy and Stuttgart, Germany.

1. Salmon-pink double flowers, composed in round, small sprays; and
2. An upright habit.

DESCRIPTION OF THE PHOTOGRAPH

This new *Dianthus* plant is illustrated by the accompanying photograph. The photograph shows the whole plant, including the flowers and foliage and buds. The colors shown are as true as can be reasonably obtained by conventional photographic procedures. The photo is of an 11-week-

2

old plant of 'KLEDP19289'. The photo was taken in Stuttgart, Germany indoors, in April 2016.

DESCRIPTION OF THE NEW VARIETY

5

The following detailed descriptions set forth the distinctive characteristics of 'KLEDP19289'. The data which define these characteristics were collected from asexual reproductions carried out in Latina, Italy. Data was collected in May 2019 on plants that were potted in week 38 of 2018. Color references are to The R.H.S. Colour Chart of The Royal Horticultural Society of London (R.H.S.), 5th edition (2007).

10

Classification:

Family.—Caryophyllaceae.

Botanical.—*Dianthus caryophyllus*.

Common.—Pot carnation.

Designation.—'KLEDP19289'.

15

Parentage:

Female parent.—'DCP-2009-0047' (unpatented).

Male parent.—'DCP-2007-0035' (unpatented).

20

Plant:

Propagation type.—Vegetative stem cuttings.

Time to produce a rooted young plant.—4 weeks.

Root description.—Fine and white, RHS 161D, habit is lanceolate-shaped.

Plant form.—Upright.

Plant height.—23.0 cm.

Plant diameter or spread.—26.0 cm.

25

Lateral branches:

Length.—22.0 cm.

Diameter.—0.2 cm.

Internode length.—5.0 cm.

Node length.—0.4 cm.

Node diameter.—0.1 cm.

30

35

COMPARISON OF 'KLEDP19289' WITH PARENTAL LINES AND KNOWN VARIETY

‘KLEDP19289’ is distinguished from the parental lines as described in Table 1.

TABLE 1

Comparison with Parental Lines			
Characteristic	'KLEDP19289'	Female Parent 'DCP-2009-0047'	Male Parent 'DCP-2007-0035'
Flower color	Salmon-pink	Yellow with purple stripes	Light pink

‘KLEDP19289’ can be compared to the commercial *Dianthus* variety ‘Sorbet’ (unpatented). Differences between the varieties are described in Table 2.

TABLE 2

Comparison with Similar Variety		
Characteristic	'KLEDP19289'	'Sorbet'
Flower color	Salmon-pink	Yellow-orange
Earliness to flower	Early	Medium-early

We claim:

1. A new and distinct variety of *Dianthus* plant designated 'KLEDP19289' as illustrated and described herein.
